UNITED STATES PATENT OFFICE.

FREDERICK BRUGNER, OF SOUTH BOSTON, MASSACHUSETTS, ASSIGNOR OF ONE-HALF
TO CAROLINA BRUGNER, OF SOUTH BOSTON, MASSACHUSETTS.

COMBINATION STEP AND EXTENSION LADDER.

Application filed February 12, 1927. Serial No. 167,725.

This invention relates to a combination step and extension ladder, that is, to a ladder structure which is convertible into either a step ladder or an extension ladder.

5 One of the features of the invention relates to the manner of connecting the two ladder sections which permits them to function either as a step ladder or as an extension ladder.

10 Another feature of the invention is a novel construction by which the ladder structure may be converted into a trestle.

Still another feature of the invention relates to a novel construction which permits the ladder structure to be used as a step ladder either on the ground or on a flight of stairs.

Other features of the invention relate to improvements in ladder constructions which will be more fully hereinafter set forth.

In order to give an understanding of the invention I have illustrated in the drawings a selected embodiment thereof which will now be described after which the novel features will be pointed out in the appended claims.

Fig. 1 is a side view of a ladder structure embodying my invention showing it in full lines in the form of a step ladder and showing in dotted lines one of the ladder sections arranged as it would be when the device is an extension ladder:

Fig. 2 is a view showing a device in the form of an extension ladder;

35 Fig. 3 is a sectional view of an additional ladder section which may be employed when the device is functioning as an extension ladder;

Fig. 4 is an enlarged vertical sectional view through the upper portion of the ladder structure when it is functioning as a step ladder;

Fig. 5 is a section on the line 5—5, Fig. 4; Fig. 6 is a view of the ladder structure

45 showing it in use as a trestle;
Figs. 7 and 8 are fragmentary sectional

views showing details of the trestle structure;

Fig. 9 shows the ladder arranged as an extension step ladder and used on a flight of stairs;

Fig. 10 is an enlarged section on the line 10—10, Fig. 2;

Fig. 11 shows another adaptation of the invention for use on a flight of stairs;

Fig. 12 is a perspective view of the foot portion of the ladder;

Fig. 13 is a fragmentary perspective view illustrating the means for supporting the upper ladder section when the ladder is being used as an extension ladder. 60

My improved ladder comprises two ladder sections 1 and 2. The ladder section 1 is shown as having treads 3 and the ladder section 2 is constructed to be used either as a brace for the ladder section 1 when the device is functioning as a step ladder as shown in Fig. 1 or as an extension section when the device is used as an extension ladder. 65

The ladder section 1 comprises the usual sides 4 which are connected by the treads 3 and at the upper end said sections 4 are connected by a cross-piece 5 which is rigidly secured to the two sections. This cross-piece has hinged thereto a top tread member 6, said tread member being secured to the cross-piece 5 by means of the hinges 7. When the tread member is in operative position it rests on the upper ends 8 of the sides 4 and it is shown as detachably retained in this position by a hook 9 connected to the under side of the top tread 6 and adapted to hook into an eye 10 on the back side of the cross-piece 5. 75 80 85 90 95 100

The ladder section 2 is made with two side pieces 11 which are connected by rounds 12. The sections 1 and 2 are connected at their upper ends by a novel means so as to permit them to function either as a step ladder or as an extension ladder.

Each side 4 of the ladder section 1 has secured thereto and extending laterally therefrom an arm 13, each arm 13 terminating in an inwardly-directed flange 14 that overlies one of the sides 11 of the ladder section 2. Each flange 14 is specially shaped, it having the lower portion 15 which co-operates with the corresponding side 11 of the ladder section 2 when the ladder is functioning as a step ladder and the upper portion 16 which co-operates with the side 11 of the ladder 2 when the ladder is converted into an extension ladder. The two portions 15 and 16 of each flange have an angular relation to each other, the portion 16 extending parallel to the side 4 of the ladder section 1 and the portion 15 extending parallel to the ladder section 2 when the ladder is functioning as a step ladder. The upper 110

round 17 of the ladder section 2 extends beyond the sides 11 as shown at 18 and the extended ends 18 are adapted to rest on the arms 13 when the ladder is functioning as a 5 step ladder. The upper end of the sides 11 are bevelled or cut away as shown at 19 and are adapted to rest against the cross-piece 5. When the ladder is converted into a step ladder, therefore, the sides 11 are 10 engaging the portions 15 of the flanges 14, the end of the sides are resting against the cross-piece 5 as shown at 19, and the ends 18 of the upper rounds 17 are resting on the arms 13. This makes a very rigid and 15 strongly braced structure.

Each side 4 of the ladder section 1 is provided with a hook-shaped brace member 20 which is pivoted to the ladder section 1 at 21 and is adapted to hook into an eye 22 20 carried by the side of the ladder section 2 thereby to maintain the ladder sections in their step ladder position.

To convert the step ladder into an extension ladder the brace hooks 20 are disconnected from the ladder section 2 and the lower end of said ladder section 2 is then swung toward the ladder section 1, the extensions 18 of the rounds 17 forming a sort of trunnion or pivot on which the ladder 30 section 2 swings. This swinging movement will carry the upper end of the ladder section 2 out from under the upper tread 6 and bring the sides 11 of said ladder section 2 against the portions 16 of the flange 14. 35 The ladder section 2 is then in parallel relation to the ladder section 1 and can be moved upwardly on the ladder section 1 as shown by dotted lines Fig. 1, or by full lines Fig. 2.

The lower end of the ladder section 2 has 40 a supporting member 23 connected thereto by which it may be detachably connected to any of the treads 3 of the ladder section 1. This member 23 comprises two connected arms 24 which are pivotally mounted on the lower round 12. Each arm 24 has the straight rest portion 25 which is adapted to lie flatly on one of the treads 3 as shown in Figs. 2 and 13, the exterior of each 45 straight portion being bent downwardly to overlie the front edge of the tread. The ladder section 2 may be extended more or less as desired and the supporting member 23 may be hooked over any one of the treads 3 of the ladder section 1.

50 When the ladder is thus converted into an extension ladder the ladder section 2 is held in proper position relative to the upper end of the ladder section 1 by the portion 16 of the flange 14, said portion 16 forming 55 a shoe or guide on which the ladder section 2 may move.

The supporting member 23 holds the lower portion of the ladder section 2 in proper relation to the ladder section 1. As an additional means of security each of side sec-

tions 4 of the ladder section 1 has an ear 26 secured thereto and extending therefrom which is provided with an aperture 27. These ears are situated on the outside of the sides 11 of the ladder section 2 when the 70 two ladder sections are arranged as an extension ladder. A retaining pin 28 is adapted to be inserted through the apertures 27 underneath the sides of the ladder section 2, and said pin thus acts as an additional 75 means for holding the ladder sections in proper relation when they are functioning as an extension ladder.

29 indicates an additional ladder section which may be detachably secured to the ladder section 2 when the device is converted into an extension ladder for the purpose of making a longer ladder. The ladder section 29 is slightly narrower than the ladder section 2 so that the sides of the ladder section 85 29 rest between the sides 11 of the ladder section 2. This ladder section 29 is provided with hooks or clips 30 adapted to hook over certain of the rounds 12 of the ladder section 2 as shown in Fig. 2.

The ladder may also be used as a trestle. For this purpose the ladder sections 1 and 2 are adjusted to form a step ladder and the ladder section 29 is supported by the step 90 ladder in an upright position.

31 indicates a supporting board which is adapted to rest on one of the treads 3 of the ladder section 1 and one of the rounds 12 of the ladder section 2. This supporting board 31 has clips or hooks 32 at one end which embrace the tread 3. The board is also provided on each side with a notch 33 adapted to receive the ends of the sides of the ladder section 29 as shown in Figs. 6 and 7. This ladder section 29 is inserted 105 between the next to the upper round 12 and the upper tread member 6, the lower ends of the sides resting in the notches 33. The engagement of the ladder section 29 with the round 12 and upper tread 6 prevents the 110 upper end of said ladder from swinging toward the right Fig. 6. The engagement of the hook or clip 32 with the tread 3 and the engagement of the lower ends of the side of the ladder section 29 prevents the 115 ladder section from swinging to the left. When supported as shown in Fig. 6, therefore, the ladder section 29 will be held firmly in upright position and may be used as a 120 trestle.

When said ladder is to be used on a flight of stairs as shown in Fig. 9 the upper tread section 6 is unlocked and swung into the dotted line position Fig. 4, the bracing hooks 20 are disconnected from the ladder section 125 2 and the lower end of the ladder section is then swung toward the ladder section 1 sufficiently to free the upper ends of the sides 11 from the cross piece 5. When this is done the ladder section 2 may be moved 130

upwardly into a position such as shown in Fig. 8. It is held in this position by means of an auxiliary brace member 34 which is pivoted to the ladder section 1 at 35. The 5 free end of the brace member 4 is provided with an eye 36 and it is connected to the ladder section 1 by the pin 28, the ladder being withdrawn from the ears 26 and inserted through apertures formed in the 10 lower end of the sides 11 of the ladder section 2. If desired, the ladder section 29 may be secured to the upper end of the ladder section 2 when it is thus adjusted for use on stairs thus increasing the length of 15 the ladder.

I have shown the lower ends of the ladder sections 1 and 2 as having feet or rests detachably secured thereto. Each rest comprises a base member 37 and two socket 20 members 38, each socket member adapted to receive the lower end of a side of the ladder section. The socket members 38 have enclosing walls which surround the lower ends 25 of the sides of the ladder section. Each socket member, therefore, is open at the top but is enclosed on the sides and bottom. The ladder sides are locked in the socket members by means of a rod 39 which extends transversely through the apertures in 30 the side walls of the socket members and through apertures in the ladder sides. The same construction may be used on both the ladder sections 1 and 2.

In Fig. 11 I have shown the ladder as 35 adapted for use on stairs as a step ladder only. In this embodiment the ladder section 1 is held in its desired inclined position by a brace member 40 which is connected to the ladder section 1 in the same

way as shown in Fig. 4 but is shorter than 40 the ladder section 2.

I claim:

1. A convertible step ladder comprising two ladder sections, one of which has treads and the other of which functions as a brace 45 for the first-named section, a supporting board removably supported by said ladder sections, said board having notches, and an additional ladder section adapted to be inserted between the sides of the ladder section 50 functioning as a brace member, with its lower end resting on the board and its sides engaging said notches, said additional ladder section being braced in one direction by engagement with the upper tread of one ladder section and a round of the other ladder section, and means associated with said support to brace the additional ladder section against movement in the other direction. 55

2. A convertible step ladder comprising two ladder sections of which one functions as a brace for the other, and a foot member for the said other ladder section, said foot member comprising a base member and socket members rigidly secured thereto and 60 into which the lower ends of the sides of the ladder section is received, each socket member having enclosing side walls which entirely enclose the lower end of one of the 65 sides of the ladder section, and a locking rod extending transversely through the side walls of the socket members and through the ladder section thereby to lock the socket members to the section. 70

In testimony whereof, I have signed my 75 name to this specification.

FREDERICK BRUGNER.
